(57) **CLAIM**

The ornamental design for a display screen with graphical user interface for a watch, as shown and described.

DESCRIPTION

FIG. 1 is a right front perspective view of a first embodiment of a display screen with graphical user interface for a watch showing our new design in a use configuration within an environment;

FIG. 2 is a front view of the display screen with graphical user interface for a watch of FIG. 1; and,

FIG. 3 is a front view of a second embodiment of the display screen with graphical user interface for a watch showing our new design.

The evenly broken lines in FIGS. 1-3 depict portions of the display screen with graphical user interface that form no part of the claimed design. The dotted-dashed broken lines in FIGS. 1-3 depict environmental subject matter that form no part of the claimed design.

1 Claim, 3 Drawing Sheets
